CONVERSION OF HYDROCARBONS

Du Bois Eastman, Port Arthur, Tex., assignor, by
mesne assignments, to The Texas Company,
New York, N. Y., a corporation of Delaware

Application November 9, 1940, Serial No. 365,056

3 Claims. (Cl. 196—49)

This invention relates to a combination catalytic cracking and thermal cracking process for the conversion of hydrocarbons to convert the same to gasoline hydrocarbons suitable as high anti-knock motor fuel.

The invention contemplates a process in which the charging oil is subjected to conversion in contact with a material having an adsorptive surface, such as catalysts of the silica-alumina type, capable of catalyzing the conversion reactions and in which the products of conversion are separated from the catalyst and subjected to thermal conversion in contact with heated cycle condensate formed in the process to effect additional conversion into gasoline hydrocarbons.

When hydrocarbon oil is subjected to catalytic cracking it is found that the insufficiently converted products, that is, particularly, the constituents of the kerosene and gas oil boiling ranges, are not as well suited for further catalytic cracking as the raw charging stock and it is more advantageous to subject such insufficiently converted constituents to thermal cracking than to either recycle them to the catalytic conversion zone or crack them in a separate catalytic cracking zone. In accordance with the invention these insufficiently converted constituents are passed through a heating zone and combined with the cracked products from the catalytic cracking zone so as to effect further conversion.

In the process the raw charging stock such as straight run gas oil, is passed through a heating zone wherein it is heated to a desired conversion temperature and directed into a catalytic cracking chamber containing a bed of catalytic material, the resultant products of conversion are withdrawn from the catalyst bed and directed into a subsequent thermal conversion chamber wherein the products of the catalytic cracking are subjected to thermal conversion in contact with heated cycle condensate, the resultant products of the thermal conversion are separated into vapors and residue and the vapors fractionated to recover the desired gasoline or motor fuel distillate and obtain a reflux condensate which is passed through a heating coil and combined with the products from the catalytic cracking zone, as stated. In accordance with the invention the cycle condensate is heated to a cracking temperature to effect conversion thereof into lower boiling constituents of the gasoline boiling range and is then combined with the catalytically cracked products and the admixed products subjected to further thermal conversion.

The invention makes it possible to operate at a relatively low cracking per pass and high charging rate in the catalytic cracking zone so as to thereby greatly increase the life of the catalyst and yet obtain a high ultimate yield of anti-knock gasoline as a result of the additional

conversion in the subsequent thermal conversion zone.

For the purpose of more fully explaining the invention reference is now had to the accompanying drawing which shows one form of apparatus adapted for practicing the invention.

In the apparatus illustrated the catalytic cracking stage of the process is practiced by heating the raw oil or charging stock in a heating coil 10, suitably disposed in a furnace 11, to the desired conversion temperature and passing the heated oil to a catalyst case 12 containing a bed of catalytic material. In practice, a plurality of catalyst cases are employed so as to provide for the reactivation of the catalyst without disturbing the continuity of the process. The products of the catalytic cracking operation are conducted through a line 13 to a thermal reaction chamber 14 which is suitably insulated against heat loss. The reaction chamber illustrated is of the low liquid level type being provided with a residue draw-off line 15 and a vapor line 16 extending from a lower section of the reaction chamber to a fractionating tower 17. The tower 17 is equipped with suitable fractionating elements such as bubble trays or the like and with the necessary cooling and refluxing means to accomplish the desired fractionation. The reflux condensate comprising constituents higher boiling than gasoline is withdrawn from tower 17 through a line 18 and is conducted by pump 19 and line 20 to a heating coil 21 suitably disposed in a furnace 22 for subjecting the condensate to a cracking temperature, and the heated products from coil 21 are passed through a transfer line 23 to the reaction chamber 14 or to the transfer line 13 so that the heated cycle condensate may be combined with the conversion products from the catalytic cracking chamber 12 and the admixed products subjected to thermal conversion in reaction chamber 14. The overhead vapors from the tower 17 pass to a condenser 24 and the gasoline or motor fuel distillate is collected in a receiving drum or gas separator 25, the liquid distillate being withdrawn through a line 26. Uncondensed components consisting essentially of normally gaseous hydrocarbons pass through a line 27 to an absorber 28. The charging oil for the process is charged by a pump 29 through a line 30 having a branch line 31 extending to the absorption tower 28 and another branch line 32 communicating with a line 33 which extends to the heating coil 10, so that the charging oil may either be passed directly to the heating coil 10 or into the absorption tower 28, or a portion may be passed directly to the heating coil and the other portion introduced into the absorption tower. The charging oil introduced into the absorption tower absorbs normally gaseous constituents particularly C₃ and C₄ hydrocarbons and the en-

riched oil is drawn from the bottom of the tower and directed by a pump 34 through line 35 thence to line 33. The unabsorbed gases leave the tower through a gas line 36.

In practicing the invention the use of the synthetic silica-alumina type of catalysts is recommended. Various acid-treated and metal-substituted clays such as the Super-Filtrols and acid-treated and metal-substituted natural or artificial zeolites, such as the artificial zeolite known as Doucile may be employed. Various metals such as uranium, molybdenum, manganese, lead, zinc, zirconium, nickel and the like, may be substituted in the clays or zeolites. Likewise, the combination of certain acid-treated active clays of the character of Filtrol, together with added proportions of alumina or silica or both may be employed. Alumina alone may be used under certain conditions. The synthetic alumina catalysts can be improved by the addition of other constituents such as zirconium oxide or molybdenum oxide. In practicing the invention the charging stock, such as straight-run gas oil and preferably a stock capable of being substantially completely vaporized, is heated sufficiently to maintain cracking temperatures of the order of 850° F.-1050° F. and preferably temperatures of 910° F.-1000° F. in the catalyst case. The oil is preferably heated in the heating coil so that it will be delivered to the catalyst case in a substantially completely vaporized condition and it is desirable to avoid deposition of liquid oil or condensation on the catalyst. In the catalytic operation pressures within a range from atmospheric pressure up to approximately 200 lbs. are ordinarily most efficient but in the practice of the invention it is desirable to maintain pressures approximating the upper limit of this range so as to facilitate the maintenance of reasonably high super-atmospheric pressures in the subsequent thermal conversion zone. In the recycling cracking zone the oil is subjected to temperatures upwards of 850° F. and preferably temperatures of about 900° F. to 950° F. under superatmospheric pressure of about 200 lbs. up to 600 or 800 lbs. The mixture of catalytically cracked products and products from the recycling cracking coil is maintained under temperatures of about 850° F.-925° F. under pressures approximating the pressure in the catalytic cracking zone.

In a typical example of the invention a straight-run gas oil of 650° F. end point is heated in the heating coil 10 and delivered to the catalyst case at a temperature of 980° F. wherein a pressure of 210 lbs. is maintained. The cycle condensate is subjected to cracking in the heating coil with an outlet temperature of 950° F. under 250 lbs. pressure and the admixed products from the catalytic cracking zone and from the recycling cracking coil are maintained in the thermal soaking zone at a temperature of 900° F. under 200 lbs. pressure.

In the practice of the invention the catalytic cracking of the liquid oil charge is conducted in a once-through or single-pass manner although when the charging stock contains normally gaseous constituents absorbed from the effluent gases the operation in the catalytic cracking zone will be cyclic as regards the normally gaseous constituents.

While I have described a particular embodiment of my invention for purposes of illustration, it should be understood that various modifications and adaptations thereof which will be

obvious to one skilled in the art, may be made within the spirit of the invention as set forth in the appended claims.

I claim:

5. 1. In the manufacture of high antiknock gasoline, the process that comprises passing straight-run gas oil charging stock through a single-pass catalytic cracking zone wherein the oil is subjected to cracking temperature in the presence of a catalyst adapted to promote conversion into lower boiling hydrocarbons of the gasoline boiling range, removing the resultant cracked products from said catalytic cracking zone and directing said products to a subsequent thermal cracking zone, heating cycle condensate to a cracking temperature in a heating zone and delivering the heated condensate into said subsequent thermal cracking zone wherein the admixed products are maintained at a cracking temperature of the order of 850° F.-925° F. and subjected to conversion, separating the resultant products of conversion into vapors and residue, fractionating the separated vapors to separate a reflux condensate from lighter products, and directing said reflux condensate to said heating zone as said cycle condensate.
- 10 2. In the manufacture of high antiknock gasoline, the process that comprises passing straight-run gas oil charging stock through a single-pass catalytic cracking zone wherein the oil is subjected to cracking temperature in the presence of a catalyst adapted to promote conversion into lower boiling hydrocarbons of the gasoline boiling range, removing the resultant cracked products from said catalytic cracking zone and directing said products to a separating and cracking zone wherein separation of vapors from residue takes place at cracking temperature, heating cycle condensate to a cracking temperature in a heating zone and delivering the heated condensate into said separating and cracking zone wherein the admixed products are maintained at a cracking temperature of the order of 850° F.-925° F. and subjected to conversion, conducting the separated vapors to a fractionating zone wherein the vapors are subjected to fractionation to separate a reflux condensate from lighter products, and directing said reflux condensate to said heating zone as said cycle condensate.
- 15 3. In the manufacture of high antiknock gasoline, the process that comprises passing raw charging stock in single pass through a heating coil in which the oil is vaporized and heated to a cracking temperature, directing the heated vapors in single pass through a catalyst chamber wherein the oil is subjected to cracking temperature in the presence of a catalyst adapted to promote conversion into lower boiling hydrocarbons of the gasoline boiling range, removing the resultant cracked products from said catalyst chamber and directing said products to a subsequent thermal cracking zone, heating cycle condensate to a cracking temperature in a heating zone and delivering the heated condensate into said subsequent thermal cracking zone wherein the admixed products are maintained at a cracking temperature of the order of 850° F.-925° F. and subjected to conversion, separating the resultant products of conversion into vapors and residue, fractionating the separated vapors to separate a reflux condensate from lighter products, and directing said reflux condensate to said heating zone as said cycle condensate.
- 20 4. In the manufacture of high antiknock gasoline, the process that comprises passing straight-run gas oil charging stock through a single-pass catalytic cracking zone wherein the oil is subjected to cracking temperature in the presence of a catalyst adapted to promote conversion into lower boiling hydrocarbons of the gasoline boiling range, removing the resultant cracked products from said catalytic cracking zone and directing said products to a separating and cracking zone wherein separation of vapors from residue takes place at cracking temperature, heating cycle condensate to a cracking temperature in a heating zone and delivering the heated condensate into said separating and cracking zone wherein the admixed products are maintained at a cracking temperature of the order of 850° F.-925° F. and subjected to conversion, conducting the separated vapors to a fractionating zone wherein the vapors are subjected to fractionation to separate a reflux condensate from lighter products, and directing said reflux condensate to said heating zone as said cycle condensate.
- 25 5. In the manufacture of high antiknock gasoline, the process that comprises passing straight-run gas oil charging stock through a single-pass catalytic cracking zone wherein the oil is subjected to cracking temperature in the presence of a catalyst adapted to promote conversion into lower boiling hydrocarbons of the gasoline boiling range, removing the resultant cracked products from said catalytic cracking zone and directing said products to a separating and cracking zone wherein separation of vapors from residue takes place at cracking temperature, heating cycle condensate to a cracking temperature in a heating zone and delivering the heated condensate into said separating and cracking zone wherein the admixed products are maintained at a cracking temperature of the order of 850° F.-925° F. and subjected to conversion, conducting the separated vapors to a fractionating zone wherein the vapors are subjected to fractionation to separate a reflux condensate from lighter products, and directing said reflux condensate to said heating zone as said cycle condensate.
- 30 6. In the manufacture of high antiknock gasoline, the process that comprises passing straight-run gas oil charging stock through a single-pass catalytic cracking zone wherein the oil is subjected to cracking temperature in the presence of a catalyst adapted to promote conversion into lower boiling hydrocarbons of the gasoline boiling range, removing the resultant cracked products from said catalytic cracking zone and directing said products to a separating and cracking zone wherein separation of vapors from residue takes place at cracking temperature, heating cycle condensate to a cracking temperature in a heating zone and delivering the heated condensate into said separating and cracking zone wherein the admixed products are maintained at a cracking temperature of the order of 850° F.-925° F. and subjected to conversion, conducting the separated vapors to a fractionating zone wherein the vapors are subjected to fractionation to separate a reflux condensate from lighter products, and directing said reflux condensate to said heating zone as said cycle condensate.
- 35 7. In the manufacture of high antiknock gasoline, the process that comprises passing straight-run gas oil charging stock through a single-pass catalytic cracking zone wherein the oil is subjected to cracking temperature in the presence of a catalyst adapted to promote conversion into lower boiling hydrocarbons of the gasoline boiling range, removing the resultant cracked products from said catalytic cracking zone and directing said products to a separating and cracking zone wherein separation of vapors from residue takes place at cracking temperature, heating cycle condensate to a cracking temperature in a heating zone and delivering the heated condensate into said separating and cracking zone wherein the admixed products are maintained at a cracking temperature of the order of 850° F.-925° F. and subjected to conversion, conducting the separated vapors to a fractionating zone wherein the vapors are subjected to fractionation to separate a reflux condensate from lighter products, and directing said reflux condensate to said heating zone as said cycle condensate.
- 40 8. In the manufacture of high antiknock gasoline, the process that comprises passing straight-run gas oil charging stock through a single-pass catalytic cracking zone wherein the oil is subjected to cracking temperature in the presence of a catalyst adapted to promote conversion into lower boiling hydrocarbons of the gasoline boiling range, removing the resultant cracked products from said catalytic cracking zone and directing said products to a separating and cracking zone wherein separation of vapors from residue takes place at cracking temperature, heating cycle condensate to a cracking temperature in a heating zone and delivering the heated condensate into said separating and cracking zone wherein the admixed products are maintained at a cracking temperature of the order of 850° F.-925° F. and subjected to conversion, conducting the separated vapors to a fractionating zone wherein the vapors are subjected to fractionation to separate a reflux condensate from lighter products, and directing said reflux condensate to said heating zone as said cycle condensate.
- 45 9. In the manufacture of high antiknock gasoline, the process that comprises passing straight-run gas oil charging stock through a single-pass catalytic cracking zone wherein the oil is subjected to cracking temperature in the presence of a catalyst adapted to promote conversion into lower boiling hydrocarbons of the gasoline boiling range, removing the resultant cracked products from said catalytic cracking zone and directing said products to a separating and cracking zone wherein separation of vapors from residue takes place at cracking temperature, heating cycle condensate to a cracking temperature in a heating zone and delivering the heated condensate into said separating and cracking zone wherein the admixed products are maintained at a cracking temperature of the order of 850° F.-925° F. and subjected to conversion, conducting the separated vapors to a fractionating zone wherein the vapors are subjected to fractionation to separate a reflux condensate from lighter products, and directing said reflux condensate to said heating zone as said cycle condensate.
- 50 10. In the manufacture of high antiknock gasoline, the process that comprises passing straight-run gas oil charging stock through a single-pass catalytic cracking zone wherein the oil is subjected to cracking temperature in the presence of a catalyst adapted to promote conversion into lower boiling hydrocarbons of the gasoline boiling range, removing the resultant cracked products from said catalytic cracking zone and directing said products to a separating and cracking zone wherein separation of vapors from residue takes place at cracking temperature, heating cycle condensate to a cracking temperature in a heating zone and delivering the heated condensate into said separating and cracking zone wherein the admixed products are maintained at a cracking temperature of the order of 850° F.-925° F. and subjected to conversion, conducting the separated vapors to a fractionating zone wherein the vapors are subjected to fractionation to separate a reflux condensate from lighter products, and directing said reflux condensate to said heating zone as said cycle condensate.
- 55 11. In the manufacture of high antiknock gasoline, the process that comprises passing straight-run gas oil charging stock through a single-pass catalytic cracking zone wherein the oil is subjected to cracking temperature in the presence of a catalyst adapted to promote conversion into lower boiling hydrocarbons of the gasoline boiling range, removing the resultant cracked products from said catalytic cracking zone and directing said products to a separating and cracking zone wherein separation of vapors from residue takes place at cracking temperature, heating cycle condensate to a cracking temperature in a heating zone and delivering the heated condensate into said separating and cracking zone wherein the admixed products are maintained at a cracking temperature of the order of 850° F.-925° F. and subjected to conversion, conducting the separated vapors to a fractionating zone wherein the vapors are subjected to fractionation to separate a reflux condensate from lighter products, and directing said reflux condensate to said heating zone as said cycle condensate.
- 60 12. In the manufacture of high antiknock gasoline, the process that comprises passing straight-run gas oil charging stock through a single-pass catalytic cracking zone wherein the oil is subjected to cracking temperature in the presence of a catalyst adapted to promote conversion into lower boiling hydrocarbons of the gasoline boiling range, removing the resultant cracked products from said catalytic cracking zone and directing said products to a separating and cracking zone wherein separation of vapors from residue takes place at cracking temperature, heating cycle condensate to a cracking temperature in a heating zone and delivering the heated condensate into said separating and cracking zone wherein the admixed products are maintained at a cracking temperature of the order of 850° F.-925° F. and subjected to conversion, conducting the separated vapors to a fractionating zone wherein the vapors are subjected to fractionation to separate a reflux condensate from lighter products, and directing said reflux condensate to said heating zone as said cycle condensate.
- 65 13. In the manufacture of high antiknock gasoline, the process that comprises passing straight-run gas oil charging stock through a single-pass catalytic cracking zone wherein the oil is subjected to cracking temperature in the presence of a catalyst adapted to promote conversion into lower boiling hydrocarbons of the gasoline boiling range, removing the resultant cracked products from said catalytic cracking zone and directing said products to a separating and cracking zone wherein separation of vapors from residue takes place at cracking temperature, heating cycle condensate to a cracking temperature in a heating zone and delivering the heated condensate into said separating and cracking zone wherein the admixed products are maintained at a cracking temperature of the order of 850° F.-925° F. and subjected to conversion, conducting the separated vapors to a fractionating zone wherein the vapors are subjected to fractionation to separate a reflux condensate from lighter products, and directing said reflux condensate to said heating zone as said cycle condensate.
- 70 14. In the manufacture of high antiknock gasoline, the process that comprises passing straight-run gas oil charging stock through a single-pass catalytic cracking zone wherein the oil is subjected to cracking temperature in the presence of a catalyst adapted to promote conversion into lower boiling hydrocarbons of the gasoline boiling range, removing the resultant cracked products from said catalytic cracking zone and directing said products to a separating and cracking zone wherein separation of vapors from residue takes place at cracking temperature, heating cycle condensate to a cracking temperature in a heating zone and delivering the heated condensate into said separating and cracking zone wherein the admixed products are maintained at a cracking temperature of the order of 850° F.-925° F. and subjected to conversion, conducting the separated vapors to a fractionating zone wherein the vapors are subjected to fractionation to separate a reflux condensate from lighter products, and directing said reflux condensate to said heating zone as said cycle condensate.

DU BOIS EASTMAN.
